SHIPPING CASE

Original Filed Feb. 8, 1923

Fig. 4.

UNITED STATES PATENT OFFICE

JOSEPH BRADFORD WARDWELL, OF STAMFORD, CONNECTICUT

SHIPPING CASE

Application filed February 8, 1928, Serial No. 617,813. Renewed January 10, 1930.

The invention relates to an improvement in shipping cases, particularly those for use in the shipment of valuable goods.

It is the object of the invention to provide a shipping case highly resistant to the entry of damaging materials and elements without the leaving of palpable traces that such entry may have occurred.

There is readily available a variety of means for making the body portion and the cover portion of a shipping case individually resistant, to various degrees, to the entry of damaging materials and elements. An obvious method of accomplishing this is to use a one-piece body portion and a one-piece cover portion of some suitable material. However, a case composed of such individually resistant portions fails of the purpose of making the closed case resistant, unless the joint between the two portions be made 20 resistant to a proper degree.

A loose joint facilitates the entry through it, without the leaving of evidence, of such damaging materials and elements as water, particles from other cargo and the tools of a pilferer. This loose joint enables a pilferer, without leaving any evidence of tampering, readily to locate the locks, saw through enough of them to gain entry into 30 the case, remove the goods and the undamaged locks, and close up the case by using the undamaged locks a second time. This loose joint often enables a pilferer to remove goods through it with a hooked wire; and a loose joint contributes to weakness, 40 rather than to strength, in a case.

For protection against pilferage alone, it has heretofore been proposed to lock the body and cover portions of a case together by means of spring-pressed hooks disposed entirely within the case, except the fastenings thereof. Such locking mechanisms have the disadvantage that, however careful be the relative positioning of the two 50 principal parts, it is necessary, in order to make sure that the hooks will catch, to allow, between the body and cover portions, for lost motion which must insure a loose joint.

An important object of the invention is

therefore to provide means whereby the joint between the body and cover portions is rendered resistant to a degree varying with the particular requirements. I accomplish this by using an improved locking mechanism connecting the body and cover portions in such a way that the said joint is susceptible of being made initially tight when the case is first closed, and is kept tight by the successive retention of substantially all of each of any subsequent pressures tending to tighten the joint. Such pressures would include, in addition to those purposely applied, the weight of packages upon the case, the pressures created by turning the case over in handling, and the like.

Another important object of the invention is to provide means whereby, although pilfering entry be secured by means such as destroying a board, the body and cover portions cannot again be put together, even with the replacement of the destroyed board, with the same locking mechanisms with which they were originally put together.

For a full understanding of the invention, reference is made to the accompanying drawings in which

Fig. 1 is a perspective view of a shipping case, parts being broken away to show the application of the invention;

Fig. 2 is a fragmentary plan view showing a modification thereof; and

Figs. 3 and 4 are perspective views of the component parts of the lock proper.

In the drawings Fig. 1 represents a simple form of shipping case composed of the body portion 10 and the cover portion 11.

As indicated a plurality of locks may be applied at different points for interlocking the cover and the body portions of the case. The number and location of the locks is a matter of choice or judgment. As indicated in Fig. 2, the lock may be applied in a corner instead of on the sides or ends.

The locking mechanism comprises principally two members which are initially secured separately to a wall of the body portion and to the cover portion, respectively. The locking mechanism is similar to construc-

tions of the prior art to the extent that the said two members are brought into interlocking engagement by the closing movement of the cover.

6 The specific arrangement, however, is as follows:

The member attached to the inside of the cover is preferably a strong jointed angular bar 12 one portion of which has perforations 13 for attachment to the cover and the other portion of which enters into engagement with the complementary part 14 of the lock. This complementary part consists of a plate 15 having a recess 16 for receiving the bar 12 and housing detent mechanism composed of a disk 17 and a spring 18.

10 The recess 16 defines a vertical wall 19 and an inclined wall 20 on the opposite side. The bar 12 normally moves in contact with wall 19 and the disk 17 and spring 18 are disposed between bar 12 and the wall 20. An abutment 23 at the upper end of plate 15 bears upon the edge of the bar 12 and co-operates with the wall 19 to guide the bar 12 in a 15 prescribed vertical path.

20 The spring 18 bears upwardly against the disk 17 and thus continuously exerts pressure against it tending to wedge it into the converging space defined by the free edge of the bar 12 and the wall 20 of plate 15.

25 When bar 12 moves downwardly, or generally into engagement with the member 14, it comes into contact with disk 17 and rolls it along wall 20 while spring 18 continuously maintains it in contact with the edge of the bar and the wall 20. The bar 12 is thus free to move inwardly into the member 14, but reverse movement is prevented by the automatic binding action of disk 17. The pressure of the spring 18 produces such a frictional contact between disk 17 and the bar 12 that sliding movement of bar 12 is made impossible. Any relative movement would involve a rolling of the disk. A rolling of the disk, however, would tremendously increase the wedging pressure. In fact, such wedging pressure would increase in proportion to the force applied on bar 12 tending to withdraw it. The wedging pressure is such that reverse sliding of the bar 12 will not occur even if the surfaces coming into contact are polished and oiled.

30 In contradistinction to the prior art, the lock described needs no fine adjustment. It merely requires an approximate vertical alignment of bar 12 with the channel between wall 19 and abutment 23. The joint in the bar 12 contributes to this alignment. The free end of the bar may be slightly rounded so that it readily enters the part 14. The cover then can be moved inwardly to the very limit by applying sufficient pressure. The lock is effective wherever this limit is reached. A particular relative position be-

tween the bar 12 and member 14 is immaterial.

It sometimes happens that boards tend to warp and cause a slight change of relative position between the cover and the body portion. With my construction no outward movement is possible and an inward movement would be automatically taken up by the lock so that a looseness or opening-up is made practically impossible.

35 One special purpose of the invention is to conceal effectively the position of the locks, and other fastenings of the case, so as to discourage pilferage attempts from the very beginning.

40 The portion 14 comprises plate 15 and a cover plate 15a for the recess 16. In the particular instance the cover plate is co-extensive with the plate 14 and has holes 24a and 25a registering with holes 24 and 25 in 45 plate 15.

45 Holes 24 and 24a are screw holes through which the lock member 14 is secured to the side or end of a casing as shown in Fig. 1, while 25 and 25a serve similarly to secure the 50 lock in a corner as indicated in Fig. 2.

55 While the locking mechanism thus far described is complete and highly efficient for the purposes for which it is intended, I prefer to make provisions which make a second 60 use of the same lock impossible. To this end I propose to, generally provide means whereby the plate 15 and the cover plate 15a are inseparably interlocked during the application of the locking mechanism i. e. during 65 the closing of the cover upon the box and the concurrent movement of the bar 12 into locking position.

70 While within the scope of this phase of my invention various means and ways may 65 be available, I propose to use the bar 12 itself as the element for interlocking the plates 15 and 15a. As is indicated in Fig. 3, the plate 15 may have one or more strap elements 26, 27 and the cover plate 15a may have 75 a complementary strap member 28 so disposed relatively to each other and the bar 12 as to make movement of the plates 15 and 15a away from each other impossible without substantially destroying the lock as a working unit. The strap 28 extends into a recess 29 in the plate 15. As the bar 12 moves into locking position, the strap 28 and the straps 26 and 27 are disposed upon relatively opposite sides of bar 12 and effectively prevent 80 separation of plates 15 and 15a from each other. Access to the locking elements 17 and 18 is therefore made impossible except by mutilating the lock and practically destroying it.

85 This feature, aside from the advantage of generally making a re-use of a lock impossible, contributes in its own way toward making a pilfering entry without leaving evidence thereof a difficult problem.

Battens 30 prevent the entry of cutting tools into the joint between the body and cover portions, and serve as a shoulder for packing means to make the said joint watertight.

5 I prefer to place two pin points 31 on the portion 14 on opposite sides of the channel for the bar 12 to protect the bar from the action of cutting tools and to serve as markers to facilitate the positioning and the alignment of the bar 12 on the cover.

10 The pairs of pin points 31 project above the upper edges of the body 10 of the box, and are located in substantial alignment with 15 the respective recesses into which the bars 12 are to be locked. To insure that the straps 12 are properly positioned to engage the complementary parts of the lock, portions 20 14 are secured in place and the cover 11 is applied and pressed down upon the pins 31. Upon removing the cover, the lower face will 25 then bear four indentations which show the two places at which the bars 12 must be secured for the parts to engage when the cover is finally applied to the box.

30 I am fully aware that within the scope of the invention the interlocking of the plate 15 and cover 15a could be carried out in various other ways. It is also obvious that there is considerable latitude in respect to the detail arrangement generally.

I claim:

1. In a shipping case, a body portion, a cover portion, and a locking mechanism comprising a member connected to a wall of the body portion and a member connected to the cover portion, the said members being constructed and arranged to enter freely into interlocking engagement when the cover is moved to closing position and being operative in several relative positions to prevent substantial relative movement of the two members in reverse direction.

45 2. In a shipping case, a body portion, a cover portion, locking mechanism comprising a member connected to a wall of the body portion and a member connected to the cover portion, the said members being constructed and arranged to enter freely into interlocking engagement when the cover is moved to closing position, and means operative in a plurality of interlocking positions to prevent substantial relative movement of the two members in reverse direction.

50 3. In a shipping case, a body portion, a cover portion, locking mechanism comprising a member connected to a wall of the body portion and a member connected to the cover portion, the said members being constructed and arranged to enter freely into interlocking engagement when the cover is moved to closing position, and including means operative in all interlocking positions to prevent substantial relative movement of the two members in reverse direction, and means on the

case defining an obstruction against access to the joint between the body portion and cover portion.

4 In a shipping case, a body portion, a cover portion and locking mechanism comprising a member connected to a wall of the body portion and a member connected to the cover portion, the said members being constructed and arranged to permit unrestricted relative movement thereof in the direction effecting closure of the cover and including take-up means for automatically retaining the two members against relative movement in reverse direction, said means being effective as said two portions approach fully 75 closed position.

5 In a shipping case, a body portion, a cover portion, a take-up locking mechanism on the cover and a wall of the body portion within the case operative to interlock the cover and the body portion and effective when the cover approaches fully closed position, and means on the casing and secured thereto from within for preventing access to the joint between the cover and the body portion when the case is closed.

6 Locking mechanism for use in shipping cases, comprising a member adapted to be secured to the body portion of the casing and a member adapted to be secured to the cover, 95 said members being constructed and arranged to freely enter into interlocking engagement when the cover is moved to closing position and means operative in several interlocking positions to prevent relative movement of the two members in reverse direction.

7 Locking mechanism for use in shipping cases, comprising a member adapted to be secured to the body portion of the casing and a member adapted to be secured to the cover, 105 said members being constructed and arranged to freely enter into interlocking engagement when the cover is moved to closing position and a spring pressed detent disposed on one of the members and arranged to yield to the other member when the latter moves into interlocking engagement, said detent being constructed to rigidly interlock the two members against relative movement in reverse direction irrespective of the relative position of the two members.

8 Locking mechanism for use in shipping cases, comprising a bar adapted to be secured to the cover substantially at a right angle thereto, a plate having a recess defining two walls at an angle to each other, one of the said walls forming a slide way for the bar, a disk movably disposed in the recess adjacent the other wall, a spring tending to force the disk toward the narrow end of the recess, the arrangement being such that the disk yields to the bar when the latter is moved in one direction in the recess and firmly wedges the bar in any position against movement in 120 125 130

reverse direction, and means for securing the plate to the body portion of the casing.

9. Locking mechanism for use in shipping cases, comprising a plate member having in one face a recess defining walls slightly inclined relatively to each other, a disk movably disposed in the recess adjacent one of the walls near the relatively narrow end of the recess, a spring bearing upon the disk and tending to move it toward the narrow end of the recess, means for limiting the movement of the disk, and a bar adapted to enter the recess at the narrow end thereof, the arrangement being such that the disk yields to the movement of the bar in one direction and firmly locks it against movement in reverse direction.

10. Arrangement according to claim 9 including an abutment in the narrow end of the recess cooperating with one of the walls to define a guide for the bar.

11. Arrangement according to claim 8 including a plate co-extensive with the said plate and forming a cover for said recess, and means for securing the two plates together.

12. A shipping case having a member adapted to be secured to the inner surface of the wall of the case and having a projecting part adapted to enter the inner surface of the cover, a member projecting inwardly from the cover, and a member carried by the first member and adapted for gripping engagement with the second member to prevent removal of the cover.

13. A device adapted for use in sealing shipping cases, including a member adapted to be secured to the inner surface of a wall of the case with a part projecting above the upper edge thereof to enter the inner surface of the cover when the latter is applied, a member adapted to be carried by the cover and project inwardly therefrom, and means carried by said first mentioned member for automatically gripping the second mentioned member to prevent removal of the cover.

14. A device adapted for use in sealing shipping cases, including a member adapted to be secured to the inner surface of the wall of the case and having a substantially vertical surface, a member mounted on the first mentioned member and movable upwardly and toward said surface, a spring normally tending to hold said second mentioned member in the upper limiting position, and a member adapted to be carried by the cover and project inwardly therefrom between said surface and said second mentioned member, and to be gripped against said surface by said second mentioned member to prevent the removal of the cover with said third mentioned member.

15. A container having a body portion and a cover portion, a locking mechanism having two members, one member associated with the cover portion and the other member connected

to the body portion, and oppositely facing elements on one member adapted automatically to grip the other member nonrotatably between them in any of a plurality of interlocking positions to prevent separation of said body and cover portions.

16. A container having two portions in combination with a locking mechanism having two members, a part of one of said members being adapted to interlock with the other of said members in any of a plurality of relative positions when in predetermined alignment, each of said members being adapted to restrain one of said portions against separation from the other portion when said part is in any of said interlocking positions, said part being movable relative to the portion which it restrains to facilitate said alignment.

17. A single-use locking mechanism comprising two members, the first member having a part movable into the second member through a sole opening therein, cooperating elements on said part and in said second member adapted to lock said part within said second member, said part being formed to fill said sole opening to prevent access to said elements when effective to lock said part within said second member.

18. A container having a body portion and a cover portion, a locking mechanism having two members, one member adapted to restrain the body portion and the other member adapted to restrain the cover portion, and means associated with one of said members to mark the portion to be restrained by the other member for the location of said last member relative to said last portion to insure registry between said members, said mechanism adapted to be effective in any of a plurality of positions of relative approach of said portions to prevent substantial relative departure of said portions.

19. A container having a cover portion and a body portion, an automatic take-up mechanism including a spring-pressed detent and having two members, one member being associated with the cover portion and the other member being connected with the body portion, said container and mechanism being constructed and arranged whereby relative approach of said portions enforces a corresponding relative approach of said members, said mechanism being effective in any of a plurality of positions of relative approach of said portions to prevent substantial relative movement of said portions in reverse direction.

20. A container having a body portion and a cover portion, a locking mechanism having two members, one member being associated with the cover portion and the other member being connected to the body portion, said members being adapted to interlock in any of a plurality of positions of relative approach

of said portions to prevent substantial relative departure of said portions.

21. A single-use locking device comprising two members operative to have unobstructed movement relatively to each other in the direction in which the locking operation is effected and including means for automatically retaining the two members against relative movement in reverse direction, said means being so housed within the retaining member as to be inaccessible and theft proof against any release of said means.

22. The structure of claim 21, wherein the retaining member is formed of separate parts, said parts having portions cooperating with the retained member for preventing separation of said parts.

In testimony whereof I affix my signature.

JOSEPH BRADFORD WARDWELL.
